UNITED STATES PATENT OFFICE

2,154,980

REMOVABLE WATER-COOLED SLAG POT

Harry Fulton Gibbs, Warren, Ohio

Application February 25, 1938, Serial No. 192,656

2 Claims. (Cl. 263—47)

This invention relates to a removable, water-cooled slag pot, the general object of the invention being to provide means for facilitating the removal of slag from the draft chamber of an open hearth furnace and to prevent crystallization of the slag in the chamber, the warping of the steel walls at the outside of the chamber and to prevent the fire brick lining from sticking to the pot.

10 The invention also consists in certain other features of construction, combination and arrangement of the several parts, to be hereinafter fully described, illustrated in the accompanying drawings and specifically pointed out in the appended claims.

In describing the invention in detail reference will be had to the accompanying drawings wherein like characters denote like or corresponding parts throughout the several views, and in which:

20 Fig. 1 is a top plan view of the pot.
Fig. 2 is a longitudinal sectional view thereof.
Fig. 3 is a transverse sectional view through the chamber with the pot in place.
Fig. 4 is an end view of the pot.

25 Fig. 5 is a fragmentary side view of the sloping end of the pot.

In these drawings, the numeral 1 indicates the brick arch of the draft chamber of the furnace, which rests on the steel plates 2, supported by the steel walls 3. The pot comprises the side walls 4, the bottom 5 and the sloping end wall 6. Each of these walls are formed separate from each other and each wall is of double walled construction to provide a water space 7. The side and end walls rest on the bottom wall. Plates 8 are fastened to the edges of the bottom wall at the ends thereof and extend upwardly to engage the side walls to help hold these side walls in place and bolts 9 having nuts 10 at their ends, detachably connect the parts together, the bolts being separated from the water spaces, as shown. Some of these bolts pass through the plates 8. An inlet pipe 11 communicates with each water space and an outlet pipe 12 is provided with each space, these pipes being connected with suitable inlet and outlet means for providing a continuous supply of water to the spaces. Grooves 13 are formed in the parts to receive certain of the pipes. A fire-brick lining 14 is provided for the pot, as shown, in Fig. 3.

50 As is well known, the slag which drips from the furnace, falls into the draft chamber and crystallizes and fills the chamber, and much time and labor is required to chisel the slag from the chamber when it accumulates in a solid mass in the chamber. This water-cooled pot catches the slag and greatly reduces crystallization thereof

and by placing the pot on a steel buggy, the pot can be easily removed by removing the front wall of the furnace and pulling the buggy out of the chamber. Then the sides and end of the pot are removed by removing the bolts and then the slag 5 can be removed from the bottom member by the use of a crane.

It is thought from the foregoing description that the advantages and novel features of the invention will be readily apparent.

10 It is to be understood that changes may be made in the construction, combination and arrangement of the several parts, provided such changes fall within the scope of the appended claims.

15 What I claim and desire to protect by Letters Patent is:

1. A slag pot for a furnace adapted to be placed on a buggy comprising, a hollow bottom member having its ends open outwardly of its end-walls 20 and aligned apertures in its opposite side-walls communicating with the openings in the ends thereof, hollow side-walls resting on the bottom member and having their ends open outwardly of their end-walls and apertures in their side-walls communicating with the openings in the ends thereof, hollow end-walls disposed between the side-walls and resting on the bottom member, said end-walls having their ends open outwardly of their end-walls and communicating 25 with apertures in the side-walls thereof, plates secured to the outer sides of the side-walls adjacent their lower corners and having apertures therein registering with the apertures in the side-walls of the bottom member, elongated bolts disposed in the open ends of the bottom member and extending through the apertures in the side-walls of the bottom member and aforesaid plates, nuts threadedly disposed on the opposite ends of the bolts, elongated bolts disposed in the open ends 30 of the side-walls and extending through the side-walls thereof, nuts threadedly disposed on the opposite ends of the bolts, independent inlet and outlet water connections communicating with the interiors of the hollow members, and a lining 35 disposed against the inner sides of the hollow members of the pot.

2. A slag pot of the character described comprising hollow members having outwardly disposed openings beyond their ends and between 40 their outer walls, elongated bolts extending through the openings in the ends of the hollow members and protruding beyond their outer walls, means on the free ends of the bolts for securing the hollow members together and a lining bearing 45 against the inner walls of the hollow members.
